OVERHEAD MONORAILWAY SYSTEM

Walter C. Cox, Denver, Colo.

Application June 28, 1948, Serial No. 35,620

3 Claims. (Cl. 104—121)

1

This invention relates to improvements in rail-ways of the overhead drive type.

It is the object of this invention to produce a railway which shall be adapted for various uses and which, for the purpose of illustration, has been shown as a passenger-carrying railway, but which may be of a type to serve as a toy or for transporting material in a store or warehouse.

It is an object of this invention to produce a railway construction of such design that the cars may travel at ultra high speeds without danger of derailment.

Another object is to produce a railway construction that can be employed in hilly countries without the necessity of bringing the road bed to a smooth even grade and which, in most cases, can be built with a very small amount of grading.

A further object is to produce a railway construction in which the traction is effected between the car and an overhead insulated rail that also serves as a conductor of electricity.

The above and other objects that may become apparent as the description proceeds are attained by means of a construction and an arrangement of parts that will now be described in detail, and for this purpose reference will be had to the accompanying drawing in which the invention has been illustrated and in which:

Figure 1 is a side elevation of a railway showing a car in position for movement along a track;

Figure 2 is a section taken on line 2—2, Figure 1;

Figure 3 is a fragmentary longitudinal section taken on line 3—3, Figure 2; and

Figure 4 is a diagram showing both a top and bottom drive.

In the drawing reference numeral 5 designates a supporting surface, for example, the ground, or a floor. In the example illustrated, the railroad is an outside one and is supported on the surface of the ground. Numeral 6 designates the ties on which rail 7 is supported and to which it is attached by spikes 8, in the usual way. In the drawing a single rail has been shown. It is to be understood that two parallel rails may be used, if desired.

Positioned along the railway track are two rows of posts 9, one on each side. The posts are arranged in pairs and are connected at their tops by a bar 10 and are preferably braced by diagonal corner braces 11, as shown in Figure 2. The center portion of bar 10 is covered with a heavy layer of electrically insulating material 12.

An upper rail 13 of inverted channel cross section having spaced parallel flanges 14 joined

by a web 15 is suspended beneath bars 10 by means of inverted U-shaped straps 16 that straddle the insulated centers of bars 10. An electric current generator 17 is connected between rail 7 and channel 13 as shown in Figure 1.

The car body has been designated by reference numeral 18 and has a floor 19, side walls 20 and a top 21, as shown most clearly in Figure 2. One or more motors 22 are supported on the car floor, as shown in Figures 2 and 3. The car is supported on two trucks whose flanged wheels have been designated by numeral 23 mounted for rotation in suitable bearings 24. When the car is of moderate length, each truck comprises a single wheel only. If more than one wheel is provided for each truck, they must be connected with the car for rocking movement about a transverse pivot so that both wheels will at all times rest on the track, regardless of the track curvature. A large idler pulley 25 is mounted for rotation on its axle 26 positioned in bearings 27. A pulley 28 is secured to motor shaft 29 and pulleys 25 and 28 are encircled by a heavy flat belt 30 that passes between the pulley surface and the inner surface of web 15, as shown in Figure 3. The parts are so proportioned that the top rail will be raised a couple of inches by pulley 25 and the weight of a considerable longitudinal section of rail 13 therefore rests on the outer surface of belt 30. If the motor is now operated to move the belt in the direction of the arrow in Figure 3, the car will move towards the right by the friction between the belt and track 13.

If it is found desirable to do so, one motor may be connected with pulley 25 and the other with one of the supporting wheels 23, as illustrated diagrammatically in Figure 4.

This construction is especially well adapted for underground conveyor systems like those used for transporting mail between post offices and railway stations and similar purposes.

Flanges 14 of the overhead rail serve as guides that limit the lateral movement of the top of the car, thus making it possible to employ a single supporting rail. If two parallel spaced supporting rails are used, the car will rock if the upper surfaces of the supporting rails are not even, in which case flanges 14 could not be used.

In the drawing and in the description the car has been shown as being electrically driven and the overhead rail serving as a trolley wire or conductor. It is, of course, permissible to use an internal combustion engine for power, if desired.

What I claim is:

1. A monorailway system comprising a car sup-

porting rail, forming a track, a plurality of pairs of posts spaced along the track, the posts of the pairs being on opposite sides of the track, the upper ends of each pair of the posts being joined by a bar, an overhead rail of channel shape positioned underneath the bars, means supporting the overhead rail from the bars to permit the rail to move vertically a predetermined distance with respect to said bars, a car having at least two wheels resting in spaced relation on the supporting rail, a traction pulley pivoted for rotation about an axis transverse to the car, said pulley projecting through the roof of the car, said pulley extending into the channel of the overhead rail, the distance from the top of the supporting rail to the under surface of the web of the overhead rail being less than the distance from the bottom of the supporting wheels to the top of the traction pulley, whereby the overhead rail will be raised when the traction pulley passes under it, and means comprising a motor mounted on the car and operatively connected to the traction pulley for rotating the latter.

2. A monorail system comprising a car supporting rail forming a track, means above the track for supporting an overhead rail for limited vertical movement, a rail of channel shaped cross section supported by said means with the flanges extending downwardly a car having at least two

wheels resting in spaced relation on the supporting rail, means including said wheels and supporting rail for preventing lateral movement of the car relative to the track, a traction pulley rotatably mounted on the car adapted to engage the upper rail, means including the pulley and the flanges of the upper rail for preventing relative lateral movement of the traction pulley and the upper rail, and means for driving the pulley.

5 3. A monorail system in accordance with claim 2 wherein traction between the pulley and upper rail is effected by an endless belt passing around a peripheral portion of the pulley.
